US009940777B2

(12) **United States Patent**
Chun

(10) **Patent No.:** **US 9,940,777 B2**
(45) **Date of Patent:** ***Apr. 10, 2018**

(54) **BETTING TERMINAL AND SYSTEM**(75) Inventor: **Jay Chun**, Hong Kong (CN)(73) Assignee: **IGT**, Las Vegas, NV (US)

(*) Notice: Subject to any disclaimer, the term of this patent is extended or adjusted under 35 U.S.C. 154(b) by 0 days.

This patent is subject to a terminal disclaimer.

Primary Examiner — William H McCulloch, Jr.*(74) Attorney, Agent, or Firm* — Neal, Gerber & Eisenberg LLP(57) **ABSTRACT**

A system in a casino for playing a game, the system comprising: a network of betting terminals linked to a plurality of game tables, first players playing a first game at each of the game tables, at least one first game being a live baccarat game, wherein each of the betting terminals comprises a mechanism to display a plurality of first games occurring at the game tables in the casino so as to allow a second player at each one of the betting terminals to switch to different game tables, place bets at different first games at a same time, place a separate jackpot wager bet on a jackpot game based on the first games being played live at the game tables and select betting options, wherein the system includes a display part having a screen for showing game number and respective amounts available for betting.

BETTING TERMINAL AND SYSTEM

CROSS-REFERENCE TO RELATED APPLICATIONS

The present application is a continuing application of U.S. Ser. No. 11/497,708 filed Aug. 1, 2006, and a continuation-in-part of U.S. application Ser. No. 11/042,732, filed Jan. 24, 2005, U.S. application Ser. No. 11/198,218, filed on Aug. 5, 2005 and U.S. application Ser. No. 11/312,150, filed on Dec. 19, 2005, the entire contents of all applications which are incorporated by this reference.

BACKGROUND OF THE INVENTION

The present invention is generally directed to a betting terminal for playing a game such as a baccarat game. The invention betting terminal allows players to play different games without moving from one gaming table to another. Therefore, the invention helps to maximize the time spent by players on gaming tables while they are inside a casino and also maximize the utilization of casino floor space.

Gaming is a major form of modern entertainment. For example, baccarat is one of the more popular gambling games played in casinos or gaming establishments. As is well known, the game is played on an elongated table having a game board displayed along the upper surface of the table. The game board displays certain wagering areas, and the elongated table allows for the seating of multiple players or bettors (1-16) and the positioning of the multiple dealers (3) necessary for operating the casino game. Bettor locations are typically numbered on the table and each bettor location has an area designated for a wager on the bank hand and an area designated for a wager on the player hand. Baccarat uses a standard deck of 52 playing cards and is usually dealt from a shoe having multiple decks that have been shuffled together prior to the beginning of play. A feature of conventional live games is that the betting process is limited to a single game. The simplicity of the betting process has led to a corresponding simplicity in the relatively few types of games which may be placed during in a casino, for example, which may limit interest on the part of the player(s) and thus further limit the casino in terms of profit and payout. The embodiments described below address the above-described issues and needs.

SUMMARY OF THE INVENTION

Provided is a betting terminal for playing a game. The betting terminal comprises a network of terminals linked to different game tables where each of the terminals comprises a mechanism to switch on a plurality of games. A player at one terminal can switch to different tables and place bets at different games at a time. The games can be games of the same kind or games of different kind.

In some embodiments, a betting terminal can serve as a platform for placing bets in games like baccarat, roulette, sicbo ("dice game") as well as other common casino table games which are operated at tables linked to game and payout servers and betting terminals through an intranet. In some embodiments, the roulette and sicbo table games can be operated automatically or by human dealers, but the betting results shall be recorded automatically or manually and sent to game and payout servers electronically to allow automatic payout process.

The present invention also provides a software program or a set of software programs for carrying out any or all steps

of the betting method described herein. The baccarat game can also be incorporated into an electronic device or an entertainment gaming machine. Representative electronic devices include, but are not limited to, laptop computers or desktop computers.

BRIEF DESCRIPTION OF DRAWINGS

FIG. 1 shows an illustrative scheme of the betting terminal described herein.

FIG. 2 shows an illustrative scheme of a betting system of the present invention.

FIG. 3 shows a general layout of a betting terminal for live jackpot baccarat game.

FIGS. 4A, 4B, 4C and 4D show the detailed layout of a betting terminal for a baccarat machine; FIGS. 4E 4F, 4G and 4H show variants of the layout of the betting terminal shown in FIGS. 4A-4D.

FIGS. 5A, 5B, 5C, 5D and 5E show an embodiments of the overall design of the betting terminal.

DETAILED DESCRIPTION

Provided is a betting terminal for playing a game. The betting terminal comprises a network of terminals linked to different game tables where each of the terminals comprises a mechanism to switch on a plurality of games. A player at one terminal can switch to different tables and place bets at different games at a time. The games can be games of the same kind or games of different kind.

The betting terminal can be linked to different types of games. An illustrative general scheme of the betting terminal 100 is described in FIG. 1, which includes a switching mechanism 200 allowing a player to select a game to play. The switching mechanism 200 (not shown) can further include a game indicator 210 showing the type of game selected. The switching mechanism can be located in anywhere of the betting terminal. In some embodiments, the betting terminal is linked to a plurality of game tables. An illustrative general layout of a gaming system via a betting terminal of the present invention is provided by FIG. 2. In FIG. 2, a plurality of betting terminals (100) (three betting terminal are listed as examples) are linked via a network (220) to a plurality of game tables (300). The game tables can be conventional baccarat game tables, jackpot baccarat game tables as described in the U.S. application Ser. Nos. 11/042,732, filed on Jan. 24, 2005, 11/198,218, filed on Aug. 5, 2005 and 11/312,150, filed on Dec. 19, 2005, the teachings of which are incorporated herein by reference. In some embodiments, the game tables can be any game tables played in a casino or internet.

In one embodiment, the betting terminal described herein is one for baccarat. For example, a baccarat gaming system that allows one to play a live baccarat jackpot as described in the U.S. application Ser. Nos. 11/042,732, filed on Jan. 24, 2005, 11/198,218, filed on Aug. 5, 2005 and 11/312,150, filed on Dec. 19, 2005, the teachings of which are incorporated herein by reference.

In one embodiment, the betting terminal described herein is one for baccarat. For example, a baccarat gaming system that allows one to play a live baccarat jackpot as described in the U.S. application Ser. Nos. 11/042,732, filed on Jan. 24, 2005, 11/198,218, filed on Aug. 5, 2005 and 11/312,150, filed on Dec. 19, 2005, and Macau Patent Application Nos. 1/150, filed on Feb. 4, 2005 and 1/265, filed on Jan. 24, 2006, the teachings of which are incorporated herein by reference.

A general layout of a betting terminal for a live jackpot baccarat game is shown in FIG. 3, FIGS. 4A and 4B. FIG. 3 shows the overall layout of the betting terminal which has two screens, the upper screen (400) and the lower screen (500), shown in detail in FIGS. 4A and 4B, and a switching mechanism 200, which is not shown. Referring to FIG. 4A, upper screen 400 includes an display part (410) for displaying the rolling amount of jackpot, the center part (420) for displaying a live video of the gambling table, and a messenger screen (430) for displaying messages or game cards. The center part of the upper screen has a left section designated as Player (440), which has a small screen (450), and right section 10 designated as Banker (460), which also has a small screen (470). The small screens 450 and 470 are for display of card values of the player hand and the bank hand respectively. The current limits available for betting on Player (player hand) and Banker (bank hand) in a live baccarat game are shown in small screens 480 and 490 below small screens 450 and 470, respectively. Referring to FIG. 4B, the lower screen 500 is an operating touch screen for betting, which includes bet-option buttons (510), bet-amount buttons (520), and credit window (530). The bet-option buttons 510 include the various betting selections described above, e.g., betting for player hand (511) win with a payoff rate of 1:1, for the bank hand (512) win with a payoff rate of 1:0.95, for tie (513) with a payoff rate of 20 1:8, for Player Pairs (514) with a payoff rate of 1:11, for banker pairs (515) with a payoff rate of 1:11, and for Jackpot bet (516), the rules of which are described above. Box 517 shows the pops up when bets are placed on a particular bet option. The number inside Box 517 corresponds to the amount placed on a particular bet option. The bet-amount buttons 520 as shown in the layout, 100,500, 1000,5000, 10000, provide the players the convenience of adding up betting amounts in a fast manner.

To illustrate, for a bet of 10,000 USD or HKD, the player can simply press the “1000” button ten times to reach the desired betting amount. Note, the bet-amount buttons 520 shown are illustrative and non-exclusive. Buttons designated for other amounts, e.g., “1”, “5”, “10”, “100”, “100,000”, “1,000,000” can be readily added to the screen. The credit window 530 shows the remaining balance of a player’s credit. The player may insert bills or chips into or transfer money from a credit card account and/or a bank account to the machine to add up the credit amount from time to time. If the player desires to stop playing the baccarat game and to cash out, he may ask the operator to authorize a cash-out procedure, and then obtain the remaining balance. Still referring to FIG. 4B, the lower screen 500 further includes language selection button (540), which can switch the operation language of the baccarat game between, e.g., Chinese, English, Portuguese, Italian, French, Spanish, Russian, German, Arabic, Japanese, and Korean, etc, Rule selection button (550), which prompts the display of rules for live baccarat and Paradise Jackpot™, Cancel button (560), which allows the bettor to cancel all bets made before he presses the confirmation button on the top right hand corner of the lower screen. Operator button (570), which allows the bettor to call for assistance from the casino staff when there is machine failure or the bettor wishes to exit from the game, and Results Bars (580, 590) which display the results for previous live baccarat games. Once results of a game are confirmed, the losing bet shown in the bet option buttons (510) in the center of lower screen will disappear while the winning bet in the bet option buttons (510) in the lower screen will flash and a diagram will pop up with detailed breakdown of the payouts for each of the bet options won.

FIGS. 4C and 4D show two variants of the design of the betting terminal similar to the embodiment as described in FIGS. 4A-4B. Referring to FIG. 4C, upper screen 400 includes a display part (410) for displaying the baccarat game result and rolling amount of jackpot, a display part (420) for displaying a live video of the gambling table, and a messenger screen (430) for displaying game cards. The display part 420 has a left section designated as Player (440), which has a small screen (450), and right section designated as Banker (460), which also has a small screen (470).

The small screens 450 and 470 are for display of card values of the player hand and the bank hand respectively. The current limits available for betting on Player (player hand) and Banker (bank hand) in a live baccarat game are shown in small screens 480 and 490 below small screens 450 and 470, respectively. Still referring to FIG. 4C, the display part 420 can display Player game cards 440A and Banker game cards 460A. The messenger screen 430 shows game cards directly from a shoe in a baccarat game (not shown), 440B and 440C for the Player, and 460B and 460C for the Banker. The game cards 440A and 440B correlate to each other can have the same or different appearance. Similarly, the game cards 460A and 460B correlate to each other can have the same or different appearance. Preferably, game cards 440A, 440B, 440C, 460A, 460B and 460C are shown directly from a shoe in a baccarat game (not shown).

Still referring to FIG. 4C, the display part 410 includes a screen (412) for showing jackpot amount, display 411 showing game number (e.g., game No. 52) and respective amounts 415 available for betting on banker pairs, player pairs or tie, display 416 showing the frequency of bank hand win, player hand win and tie in past games, and display 418 showing the sequence of bank hand win, player hand and tie in past games.

Referring to FIG. 4D, the lower screen 500 is an operating touch screen for betting, which includes bet-option buttons (510), bet-amount buttons (520), and credit window (530). The bet-option buttons 510 include the various betting selections described above, e.g., betting for player hand (511) win with a payoff rate of 1:1, for the bank hand (512) win with a payoff rate of 1:0.95, for tie (513) with a payoff rate of 20 1:8, for Player Pairs (514) with a payoff rate of 1:11, for banker pairs (515) with a payoff rate of 1:11, and for Jackpot bet (516), the rules of which are described above. Box (511A) and Box (517) show the pops up when bets are placed on a particular bet option. The number inside Box 511A corresponds to the amount placed on a particular bet option on a player hand win. The number inside Box 517 corresponds to the amount placed on a particular bet option on banker hand win. Display screen (518) shows the total accepted amount of bets placed on all bet options. The bet-amount buttons 520 as shown in the layout, 50, 100, 500, 1000, provide the players the convenience of adding up betting amounts in a fast manner. Note, the bet-amount buttons 520 shown are illustrative and non-exclusive. Buttons designated for other amounts, e.g., “1”, “5”, “10”, “100”, “100,000”, “1,000,000” can be readily added to the screen. The credit window 530 shows the remaining balance of a player’s credit. The player may insert bills or chips into or transfer money from a credit card account and/or a bank account to the machine to add up the credit amount from time to time. If the player desires to stop playing the baccarat game and to cash out, he may ask the operator to authorize a cash-out procedure, and then obtain the remaining balance. Still referring to FIG. 4D, the lower screen 500 further includes language selection button (540), which currently is in Chinese and can switch the operation language of the

5

betting table between, e.g., Chinese, English, Portuguese, Italian, French, Spanish, Russian, German, Arabic, Japanese, and Korean, etc., Rule selection button (550), which prompts the display of rules for a selected game (e.g., a live baccarat and Paradise Jackpot™), Stand-by button 550A to lock the betting terminal if the better wishes to leave the terminal for a short period of time, Cancel button (560), which allows the better to cancel all bets made before he presses the confirmation button on the top right hand corner of the lower screen. Operator button (570), which allows the better to call for assistance from the casino staff when there is machine failure or the better wishes to exit from the game, and Results Bars (580, 590) which display the results for previous live baccarat games. Once results of a game are confirmed, the losing bet shown in the bet option buttons (510) in the center of lower screen will disappear while the winning bet in the bet option buttons (510) in the lower screen will flash and a diagram will pop up with detailed breakdown of the payouts for each of the bet options won. FIG. 4G depicts Results bars (900, 902, 904 and 906). Each of the results bars represents a different table and the past results at that table and is within a touch screen.

FIGS. 4F and 4H are alternative designs of the upper screen 400 as shown in FIG. 4A, which has a similar layout as the one shown in FIG. 4A except that the top left corner of the upper screen displays the words "Paradise Jackpot™" and the bottom rim has a blank bar and numbers 1 through 20 for showing the result of past games on top of the bar. FIGS. 4E and 4G are alternative designs of the lower screen of 500 as shown in FIG. 4B, which has a similar layout as the one shown in FIG. 4B except that the top rim of the lower screen 500 bears letters indicating the left side as the Player side and the right side and the Banker side, a screen at the far up-left corner indicating the maximum bet on the player hand accepted by the dealing table in a game, and a screen at the far up-right corner indicating the maximum bet on the banker hand accepted by the dealing table in a game.

FIG. 5A shows an embodiment of the top layout betting terminal 600 of the present invention. The top layout includes information Lamp 610, which can be color-changeable LED and flashes when a player wins a betting option, an upper screen 620, bottom screen 630, a ticket printer slot 640, a bill slot 650, table 660 for holding beverage drinks or ashtray, and speaker 670. In some embodiments, the ticket printer can print out ticket with bar code. In some embodiments, a player can also insert ticket with bar code to increase the credit amount that a play may have in a betting game. FIGS. 5B and 5D show two side views of the betting terminal, showing a cable path 602. FIG. 5C shows a front view of the betting terminal, showing the top layout described in FIG. 5A and speaker 670. FIG. 5E shows a back view of the betting terminal of this embodiment, showing Lamp 610, lock mechanism 690 and fan 692. In an embodiment, three betting terminals can be clustered in a unit. In some embodiments, the betting system can automatically generate commonly accepted format of past results of played games on the screen to provide references for players.

The betting terminal described above can be embodied in any form. In some embodiments, the betting terminal can be a device. In some embodiments, the betting terminal can be a virtual terminal. One of ordinary skill in the art can readily construct the betting terminal described herein.

The betting terminal described above can be used in any gaming system. In some embodiments, a betting terminal can serve as a platform for placing bets in games like 65 baccarat, roulette, sicbo ("dice game") as well as other common casino table games which are operated at tables

6

linked to game and payout servers and betting terminals through an intranet. In some embodiments, the roulette and sicbo table games can be operated automatically or by human dealers, but the betting results shall be sent to game and payout servers electronically to allow automatic payout process.

In some embodiments, the gaming system can further include a device on each dealing table to record the betting results automatically or manually and send the results to 10 server for computation of payouts. In some embodiments, such a device can be, for example, electronic scanning or reading devices known in the art, card dealing shoe with scanning device to read the cards, electronic detecting device to identify ball location on a roulette and image 15 recognition device for reading results of a dice game.

In some embodiments, the gaming system is a baccarat 20 gaming system. The gaming system can include a dealing table comprising a touch screen. The dealing table allows a dealer to perform a dealing process. The touch screen can 25 prompt the dealer of the dealing process. In some embodiments, the touch screen can provide dealing instructions. The games that can be played via the betting terminal described herein in game tables or terminals located within a single gaming establishment or throughout multiple gaming establishments. The game tables or terminals can be linked together by wire or wireless linking or connecting mechanisms. In some embodiments such linking mechanisms can be electric and/or optical cable. In some embodiments, the linking mechanism can be internet or intranet.

In some embodiments, the present invention also provides 30 a software program or a set of software programs for carrying out any or all steps of the betting method described herein. The baccarat game can also be incorporated into an electronic device or an entertainment gaming machine. 35 Representative electronic devices include, but are not limited to, laptop computers or desktop computers. In some embodiments, such electronic devices can be a cell phone, a blackberry device or a hand held device such as hand held personal computer (PC) or personal data assistants (PDAs). 40 The betting table and system described above can be readily constructed by an artisan of ordinary skill.

While particular embodiments of the present invention have been shown and described, it will be obvious to those skilled in the art that changes and modifications can be made 45 without departing from this invention in its broader aspects. Therefore, the appended claims are to encompass within their scope all such changes and modifications as fall within the true spirit and scope of this invention.

I claim:

1. A gaming system comprising:
a gaming server programmed to operate with a plurality of gaming tables and a betting terminal via a network to: communicate data which results in a player wagering display area of the betting terminal displaying a plurality of bet-option buttons, a plurality of bet-amount buttons, and a credit window, wherein the betting terminal is located remote from the plurality of gaming tables, the betting terminal is configured to display, on a video display area, a first baccarat game taking place at a first one of the plurality of gaming tables, and the betting terminal is configured to enable a player to place a wager, via the player wagering display area, on a play of the first baccarat game taking place at the first one of the plurality of gaming tables,
communicate data which results in a first area of a single player wagering display of the betting termi-

nal displaying a plurality of results bars, wherein each said results bar displays the results for at least two previously played baccarat games that occurred at other gaming tables, and simultaneous with the display, by the betting terminal, of at least one of: the display of the plurality of bet-option buttons, the display of the plurality of bet-amount buttons, and the display of the first baccarat game taking place at the first one of the plurality of gaming tables, separate from any wagers being placed on any plays of any baccarat games taking place at any of the plurality of gaming tables and responsive to the player at the betting terminal making a first input to the first area of the single player wagering display of the betting terminal which displays one of the plurality of results bars, communicate data which results in the video display area switching from displaying the first baccarat game taking place at the first one of the plurality of gaming tables to display a second baccarat game taking place at a second one of the plurality of gaming tables.

2. The gaming system of claim 1, wherein each gaming table comprises a device configured to record the betting results automatically and send the results to said gaming server for computation of payouts.

3. The gaming system of claim 1, wherein at least one of the gaming tables is a dealing table that includes a touch screen configured to one of: execute a dealing process and display dealing instructions.

4. The gaming system of claim 1, wherein said betting terminal is one of: an electronic device and an entertainment gaming machine.

5. The gaming system of claim 4, wherein the electronic device is one of: a laptop computer, a desktop computer, a cellular phone, a hand held personal computer, and a hand held personal data assistant.

6. The gaming system of claim 1, wherein the display part is further showing a frequency of bank hand wins, player hand wins and ties in the at least two previously played games, and a sequence of the bank hand wins, player hand wins and the ties in the at least two previously played games.

7. The gaming system of claim 1, wherein each gaming table comprises a device configured to record the betting results manually and send the results to said gaming server for computation of payouts.

8. The gaming system of claim 1, wherein the network comprises a wireless network.

9. A gaming system comprising:

a gaming server programmed to operate with a plurality of 50 gaming tables and a betting terminal via a network to: communicate data which results in a first area of a display of the betting terminal displaying a plurality of results bars, each result bar graphically showing the past results of at least two previously played baccarat games that occurred at the respective gaming table, wherein the betting terminal is located remote from the plurality of gaming tables and the betting terminal is configured to display, on a video display area, a baccarat game taking place at one of 55 the plurality of gaming tables;

communicate data which results in the display of the betting terminal displaying a frequency of bank hand wins, player hand wins and ties in the at least two previously played baccarat games, and a sequence of 60 bank hand wins, player hand wins and ties in the at least two previously played baccarat games;

separate from any wagers being placed on any plays of any baccarat games taking place at any of the plurality of gaming tables, enable, via a switching mechanism in the first area of the display of the betting terminal, the player to switch to a different one of the gaming tables in response to actuating one of a plurality of results bars of a player wagering display area of the betting terminal,

communicate data which results in the display of the betting terminal displaying a game number for the gaming table selected by the player and amounts available for betting on each of a banker pair, a player pair and a tie;

enable the player to place wagers at different ones of the gaming tables, via a plurality of bet-option buttons, a plurality of bet-amount buttons, and a credit window on the player wagering display area, wherein for each of the different ones of the gaming tables, available wagering options include at least the same wagering options as provided in a live game to live players at that gaming table, and the plurality of results bars displayed by the betting terminal are displayed simultaneously with the display, by the betting terminal, of the baccarat game taking place at one of the plurality of gaming tables.

10. The gaming system of claim 9, wherein each gaming table comprises a device configured to record the betting results automatically and send the results to said gaming server for computation of payouts.

11. The gaming system of claim 9, wherein at least one of the gaming tables is a dealing table that includes a touch screen configured to one of: execute a dealing process and display dealing instructions.

12. The gaming system of claim 9, wherein said betting terminal is one of: an electronic device; and an entertainment gaming machine.

13. The gaming system of claim 12, wherein the electronic device is one of: a laptop computer, a desktop computer, a cellular phone, a hand held personal computer; and a hand held personal data assistant.

14. The gaming system of claim 9, wherein each gaming table comprises a device configured to record the betting results manually and send the results to said gaming server for computation of payouts.

15. The gaming system of claim 9, wherein the network comprises a wireless network.

16. A gaming terminal comprising:

a display device;
a processor; and
a memory device which stores a plurality of instructions, which when executed by the processor, cause the processor to:
cause the display device to display, in a player wagering display area, a plurality of bet-option buttons, a plurality of bet-amount buttons, and a credit window, cause the display device to display, in a video display area, a first baccarat game taking place at a first one of a plurality of gaming tables located remote from the gaming terminal,
cause the display device to display, in a first area of a single player wagering display, a plurality of results bars, wherein each said results bar displays the results for at least two previously played baccarat games that occurred at other gaming tables,

enable a player to place a wager, via the player wagering display area, on a play of the first baccarat game taking place at the first one of the plurality of gaming tables, and

simultaneous with the display of at least one of: the 5 display of the plurality of bet-option buttons, the display of the plurality of bet-amount buttons, and the display of the first baccarat game taking place at the first one of the plurality of gaming tables, separate from any wagers being placed on any plays of 10 any baccarat games taking place at any of the plurality of gaming tables and responsive to the player making a first input to the first area of the single player wagering display which displays one of the plurality of results bars, cause the video display area 15 to switch from displaying the first baccarat game taking place at the first one of the plurality of gaming tables to display a second baccarat game taking place at a second one of the plurality of gaming tables.

17. The gaming terminal of claim **16**, which is part of one 20 of: an electronic device and an entertainment gaming machine.

18. The gaming terminal of claim **17**, wherein the electronic device is one of: a laptop computer, a desktop computer, a cellular phone, a hand held personal computer, 25 and a hand held personal data assistant.
